Primary Examiner — Catherine Ho(74) *Attorney, Agent, or Firm* — Crowell & Moring LLP(57) **CLAIM**

We claim the ornamental design for a work area screen, as shown and described.

DESCRIPTION

FIG. 1 is a top front-right perspective view of a work area screen;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom front-right perspective view thereof.

The broken lines in FIGS. 1-5, 7, and 8 illustrate portions of the article that form no part of the claimed design. The article is shown with a symbolic break in its height. The appearance of any portion of the article between the jagged symbolic break lines forms no part of the claimed design.
